UNITED STATES PATENT OFFICE.

BENJAMIN A. LOMBARD, OF STOCKTON, CALIFORNIA.

HORSE-POWER.

SPECIFICATION forming part of Letters Patent No. 357,212, dated February 8, 1887.

Application filed April 20, 1886. Serial No. 199,496. (No model.)

To all whom it may concern:

Be it known that I, BENJAMIN A. LOMBARD, a citizen of the United States, residing at Stockton, in the county of San Joaquin, State of California, have invented certain new and useful Improvements in Horse-Powers for Pumping Apparatus, of which the following is a specification, reference being had therein to the accompanying drawing.

10 The figure is a side elevation of a horse-power pumping apparatus and frame, showing the features of my invention.

The object of my invention is to construct a combined horse-power for pumping apparatus that will admit of a number of pumps being operated by the same motor.

15 The main frame of my apparatus consists of the foot-pieces B', the standards C, united at their tops by cross-pieces, and the tank-supporting cross-beams B. The standards C are secured at their lower ends to outer ends of foot-pieces B', and the outer ends of the beams B are secured to the standards C.

20 The shape of the above frame is that of a cross, the horizontal beams being connected together at a center.

The horse-power is supported upon a stand, K, within the frame-work last described. This stand K has located at proper intervals on its 25 top travelers e and a center sleeve, d. Upon the travelers e and sleeve d is seated the horse-power J, its bottom rim traversing the travelers e and its center flange, c, engaging with and traversing the rim of the sleeve d. The top rim, a, of the horse-power is corrugated. 30 Turning levers b extend outwardly from the rim of the horse-power.

A pipe, I, is inserted in the well and has an 35 enlarged head, H. Horizontal pipes G radiate from the head H and have connected to them vertical pump-cylinders D', upon which

are attached vertical discharge-pipes D, containing plungers, to which are attached horizontal pitman-levers E, whose outer ends are flexibly attached to frame-standard C. To the 45 ends of the pitman-levers E, just back of their connections with the pump-plungers, are flexibly attached pitmen F, whose lower ends are provided with rollers F' in suitable jaws, the rollers F' engaging with the surface of the corrugated rim a, the weight of the pitmen F and rollers F' keeping the rollers steady on the rim a.

The tank A is seated upon and at the center of the cross-beams B, the discharge-nozzles of 50 the vertical pipes D being located over the rim. The pipe I is inserted through the centers of flange c and sleeve d and an opening at the connection of foot piece B'.

To operate the above-described apparatus, 55 horses are attached to the levers b, setting the horse-power in motion. The corrugated rim a imparts a vertical motion to the pitmen F and levers E, setting the plungers of the pumps in motion, raising the water from the well 60 through the pipes I H G D and cylinder D', and discharging it into the tank A.

I am aware that some of the features I have described are old; but

What I claim as new and of my invention 70 is—

The combination of the frame B B' C, the stand K e d, and the horse-power having the series of inclines a, adapted for the operation through rollers F' of the series of pitmen and 75 pump-pistons, substantially as described.

In testimony whereof I affix my signature in presence of two witnesses.

BENJAMIN A. LOMBARD.
